BATTERY LIGHTING SYSTEM

Anthony N. Smith, Girard, Pa., assignor to The
Girard Model Works Inc., Girard, Pa., a corpora-
tion of Pennsylvania

Application August 15, 1933, Serial No. 685,218

8 Claims. (Cl. 46—48)

This invention relates to a battery lighting system and more particularly to such a system adapted for lighting the interior of a toy vehicle such as a railway coach.

- 5 The primary and general object of the present invention resides in the provision of a compact, simple and inexpensive battery lighting system for lighting the interior of toy bodies, particularly vehicle toy bodies such as toy railway cars.
- 10 To the accomplishment of the foregoing and such other objects as will hereinafter appear, my invention consists in battery lighting elements and their relation one to the other, as herein-after are more particularly described in the specification and sought to be defined in the claims. The specification is accompanied by a drawing, in which:

Fig. 1 is a side elevation of an inexpensive type of toy railway coach embodying my invention;

20 Fig. 2 is a plan view thereof with the top removed;

Fig. 3 is an enlarged section in the plane of the line 3—3 of Fig. 2; and

25 Fig. 4 is an enlarged section in the plane of the line 4—4 of Fig. 2.

Referring to the drawing, the lighting system of my invention is shown applied to an exceedingly simple and inexpensive form of toy railway coach and one of the advantages of the present system is the fact that because of its simplicity it may be made at a minimum of expense com-

mensurate with the toys of this character.

The coach comprises a bottom plate 12, side walls 14, and a top 16, all of which are pressed out of sheet metal. The bottom plate has appropriate bearings 18 and side flanges 20 bent downwardly at the side edges thereof, and additional flanges 22 bent downwardly at the ends thereof. The bearings 18 carry axles 24 with appropriate flanged wheels 26. The end portions of bottom plate 12 are slotted at 28 to receive the inner ends 30 of appropriate coupling means 32 for connecting the coach in the train, the coupling means 32 passing through appropriate supporting slots in the end flanges 22.

The side walls 14 are appropriately stamped and apertured in simulation of doors and windows and are secured to the bottom plate 12 by conventional tongue and slot construction as is indicated at 34 in Fig. 3. The top edges of walls 14 are flared outwardly as shown at 36 in Figs. 1 and 2. The top or roof 16 may be pressed out of a single piece of sheet metal and is provided with in-turned edges 38 which mate with and encompass the outwardly flared edges 36. The top is, in this

manner, made detachable from the body of the coach, thus giving access to the lighting system next to be described.

The lighting system comprises a metallic plate which, in the present case, is the main bottom plate 12 of the coach. This metallic plate is provided with appropriate means for holding a pair of slender cylindrical dry cells 40 and 42 in place. In the present case, the plate is bent downwardly to form troughs 44 extending in spaced parallel relation near the side edges of the car. The troughs 44 are substantially shorter than the battery cells and the metal from plate 12 at each end of the troughs is struck upwardly to form resilient retaining fingers or clamps 46. In the present case, the side walls 14 of the coach also act to help retain the cells 40 and 42 in place. It will thus be seen that the cells may be pressed downwardly through the open top of the coach into troughs 44 and are there frictionally held by fingers 46. It will be noted that the batteries are placed in reverse polarity, that is, the positive poles 50 and 52 of cells 40 and 42 pointing toward opposite ends of the coach. It may also be mentioned that for a small toy coach of the sort here disclosed, the cells 40 and 42 may be of the type used in flash-lights of the fountain pen type, these being small in diameter and fitting readily in a small space.

30 The cells 40 and 42 are spaced apart in order to provide room therebetween for a lamp socket 54. The lighting system further preferably includes a single strip of insulation 56 resting on metallic plate 12 between the cells 40 and 42.

35 The battery cells are connected in series at one end by a generally T-shaped connector 58 formed of a single piece of sheet metal, the stem portion of which is insulated from the car body and riveted to the insulation strip 56 by a rivet or eyelet 60. It will be noted from an inspection of Fig. 4 40 that bottom plate 12 is cut away at 62 in order to prevent contact between connector 58 and the car body or ground. The cross portion of connector 58 is bent upwardly and extends between the base 64 of cell 40 and the pole 52 of cell 42 45 (or vice versa, that is, the batteries may be turned around so long as the relative reversal of polarity is maintained).

50 Socket 54 comprises a threaded sleeve or shell 66 acting as one terminal of the socket and a rivet or eyelet 68 acting as the other terminal of the socket, the said eyelet passing through an insulation washer 70 occupying the bottom of shell 66. It will be noted that eyelet 68 bears directly against metallic plate 12 and thus 55

grounds the center terminal of the socket. The base of shell 66 rests in a preferably slightly cupped end 72 of the generally L-shaped connector 74. The bottom apertures of both the shell 66 and connector end 72, best shown in Fig. 3, are made sufficiently large to prevent contact with the eyelet 68, despite the fact that the riveting of eyelet 68 may be made sufficiently tight to act as sufficient holding means for connector 74. The end of connector 74 is bent upwardly and extends to one side for contact with pole 50 of cell 40, as is most clearly shown in Fig. 2.

The circuit is completed by a manually operable switch 76 pivoted directly on bottom plate 12 at 78 and provided with an outwardly projecting control arm 80. The side wall of the coach is recessed or cut away at 82 to provide clearance for movement of the control arm 80. The end switch member is of course struck out of a single piece of sheet metal. Oscillation of the switch 76 from the full line position to the broken line position shown in Fig. 2 causes the end of the switch to bear against the base 84 of cell 42, thus completing the battery circuit.

An appropriate flashlight bulb or lamp 86 is screwed into socket 54 in the usual manner and contacts through the side wall of the lamp base with the shell 66 of the socket and through its bottom or center terminal with the grounded eyelet 68 of the socket. It will be understood that the circuit runs from the socket shell 68 through connector 74 to positive pole 50 of cell 40, thence to base 64 of cell 40 and through T-shaped connector 58 to the positive pole 52 of cell 42, thence to the base 84 of cell 42 through switch 76 to ground, and from ground to the center contact or eyelet 68 of the lamp socket.

It should be noted that while the cells are held in proper position by the spring pressure of holding fingers 46, good end contact with the cells is insured regardless of this holding pressure, for pressure and movement developed by switch 76 and applied to one end of cell 42 is transmitted to the opposite end of cell 42 and thence to the base 64 of cell 40 and finally to the positive pole 50 of cell 40, that is, the contact pressure of switch 76 is applied entirely around the battery circuit.

It will be understood that the lighting system assembly comprises an appropriate metallic plate 12 with the battery supporting means, the lamp socket and the connector means including the switch but it is not essential that the said metallic plate 12 be the bottom of a toy railway coach. The entire lighting system may, for example, be applied to the roof of a toy automobile, the bulb then hanging downwardly from the roof instead of standing upwardly from the bottom as here shown.

It will therefore be apparent that while I have shown and described my invention in preferred form, many changes and modifications may be made in the structure disclosed without departing from the spirit of the invention, defined in the following claims.

I claim:

1. A battery and lamp assembly to light the interior of a toy, said assembly comprising a metallic plate, said plate being formed with spaced parallel troughs and having portions thereof struck up in opposite direction to form resilient holding fingers at said troughs, all adapted to receive and hold a pair of flash light cells in spaced parallel relation, a strip of insulation mounted on said plate between said batteries, a

lamp socket mounted between said batteries, the center contact of said socket passing through the insulation strip and metallic plate and securing the socket to said plate, means secured to said insulation strip alone and extending across and connecting the batteries at one end, means interposed between the base of the socket and the insulation strip at one end and contacting at its other end with the free end of one of the batteries, and a switch member mounted on the metallic plate and movable into engagement with the free end of the other battery.

2. A battery and lamp assembly to light the interior of a toy vehicle body, said assembly comprising a metallic plate forming a part of the toy body, said plate being struck downwardly to form spaced parallel troughs and having portions thereof struck upwardly to form resilient holding fingers at said troughs, all adapted to receive and hold a pair of cylindrical flash light batteries in spaced parallel relation, a strip of insulation mounted on said plate between said batteries, a lamp socket mounted between said batteries, the center contact of said socket passing through the insulation strip and metallic plate and securing the socket to said plate, a generally T-shaped resilient piece of metal secured to said insulation strip and extending across and connecting the batteries at one end, a generally L-shaped piece of metal interposed between the base of the socket and the insulation strip at one end and contacting at its other end with the free end of one of the batteries, and a switch member made of a single piece of sheet metal pivotally mounted on the metallic plate and movable into engagement with the free end of the other battery, thereby completing a series circuit through the batteries, the metallic plate and the lamp socket.

3. A toy railway coach comprising a coach body having a bottom plate and a removable top, said bottom plate being struck downwardly to form spaced parallel troughs and having portions thereof struck upwardly to form resilient holding fingers at said troughs, all adapted to receive and hold a pair of cylindrical flash light batteries in spaced parallel relation, a piece of insulation mounted on said plate between said batteries, a lamp socket mounted between said batteries, the center contact of said socket passing through the insulation strip and metallic plate and securing the socket to said plate, means secured to said insulation strip and extending across and connecting the batteries at one end, means interposed between the base of the socket and the insulation strip at one end and contacting at its other end with the free end of one of the batteries, and a switch member mounted on the metallic plate and movable into engagement with the free end of the other battery.

4. A toy railway coach comprising a coach body having a bottom plate and a removable top, said bottom plate being struck downwardly to form spaced parallel troughs and having portions thereof struck upwardly to form resilient holding fingers at said troughs, all adapted to receive and hold a pair of cylindrical flash light batteries in spaced relation, a piece of insulation mounted on said plate between said batteries, a lamp socket mounted between said batteries, the center contact of said socket passing through the insulation strip and metallic plate and securing the socket to said plate, a generally T-shaped resilient piece of metal secured to said insulation strip and extending across and connecting the batteries at one end, a generally L-shaped piece of metal in-
